UNITED STATES PATENT OFFICE.

CHARLES B. JOHNSON, OF CHICAGO, ILLINOIS.

HOIST.

1,412,527.

Specification of Letters Patent. Patented Apr. 11, 1922.

Application filed December 9, 1920. Serial No. 429,532.

To all whom it may concern:

Be it known that I, CHARLES B. JOHNSON, a citizen of the United States, residing at Chicago, in the county of Cook and State 5 of Illinois, have invented certain new and useful Improvements in Hoists, of which the following is a specification.

This invention relates to improvements in hoists and more particularly to that type of 10 hoist adapted to transport building materials, equipment, etc., from the ground to the upper stories of a building under construction, to the workmen; or vice versa; and to remove rubbish from the building to the 15 rubbish cart. One object is to provide a simple and efficient device of this class that is easily operated, quickly applied to or removed from the building, and the employment of which effects a great saving in time 20 and labor, thereby materially facilitating building construction generally.

With the foregoing and other objects in view the invention consists in the combination and arrangement of parts to be hereinabove 25 after fully described, pointed out in the appended claims and illustrated in the accompanying drawings which form a part of this application and in which—

Fig. 1 is a plan view of my improved 30 hoist illustrating its application.

Fig. 2 is a cross section on line 2—2 of Fig. 1.

Fig. 3 is a similar view taken on line 3—3 of Fig. 1.

Fig. 4 is a side view, partly in section, of 35 a slightly modified form of hoist illustrating its application.

Fig. 5 illustrates a slightly modified form of the device shown in Fig. 4 with the adjustable parts in an altered position.

Fig. 6 is an enlarged sectional view taken 40 on line 6—6 of Fig. 1.

Like reference characters denote corresponding parts throughout the several views.

The reference numeral 1 denotes the 45 columns of a building under construction, 2 the forms in which the concrete joists 3 are molded and 4 a temporary platform in the building adapted to permit materials received from the hoist to gravitate to the floor of the building, or to be easily loaded upon the hoist. Spaced outwardly from the 50 columns 1 I provide the oppositely disposed channelled guides or uprights 5, the channels

55 6 of a pair of guides facing each other. The guides 5 are supported in position by

the braces 7, the ends 8 of which are secured to the said guides and the opposite ends secured to the adjustable frame composed of the angle pieces 9, substantially L-shaped, the 60 ends of said pieces overlapping each other and being adjustably bolted together, as clearly shown in Fig. 1, so that the size of the frame may be varied longitudinally or transversely to enable it to be secured to 65 columns 1 of varying distances from each other and of varying diameters or thicknesses. The guides 5 are built up from the ground, from floor to floor as the construction of the building progresses, and when 70 the joists 3 are formed the braces 7 are secured thereto, as well as to the frame 9, the braces 7 being retained in position, or left, at each floor until the hoist is removed from this particular part of the building. The 75 nuts are then removed from the brace-bolts 9^a and the braces themselves removed.

Operatively arranged in the upper channelled portions 6 of the guides 5 is a sliding frame comprising the upper and lower bars 80 10, 11, end bars 12 and the vertical intermediate brace bars 13 connecting the bars 10 and 11. To the lower bar 11 I secure one end of the control cable 14 which cable runs up and over a pulley 15 carried by the block 85 16 which is secured to the guides 5, the opposite end of said cable being secured to a cable drum (not shown) whereby said cable may be wound up or paid out to raise or lower the frame 10, 11, 12. 90

The frame bar 10 has secured thereto by hinges 17 the bars 18 whereby the platform 19 is supported, said members 18 and 19 being separated by the cross bars 20. To the bars 18 the telescoping legs 21 are secured by hinges 22, said legs being secured also by hinges 23 to the lower frame bar 11. Legs 24 pivotally secured to the bars 18 are adapted for adjustable connection to the telescoping legs 21, bolts 25 serving to make 95 this connection as well as securing the sections of the said legs 21 in adjusted relation.

In the form of platform 19 shown in Figs. 1, 2 and 3 the inner end 26 of the platform is diminished in width to receive the extension 105 arms 27 which are connected by pivot bolts 28 to said platform, said arms 27 being disposed immediately adjacent said guides 5. The platform shown in Fig. 4 is provided with a frame composed of the side plates 29 110 and end plates 30, the latter having an opening therein which is normally closed by

the sliding door 31. The platform shown in Fig. 5 is identical with that in Fig. 4 except the frame 29, 30 is eliminated. The platform provided with the frame is adapted 5 to carry rubbish and the like; the platform shown in Fig. 5 is adapted to carry one or more wheelbarrows; and the platform shown in the first three figures is adapted to carry lumber, iron bars and the like.

10 Operation: The platform is adjusted with relation to the frame 10, 11, 12 by means of the legs 21, 24. This platform may be disposed at right angles to the said frame as shown in Fig. 5 or the free end of the 15 platform may be tilted above the inner end as shown in Fig. 3; or below the inner end as shown in Fig. 4. The frame 10, 11, 12 is raised in the guides 5 by means of the cable 14; when said cable is paid out from 20 its drum the frame and platform will be lowered by gravity, and when the cable is wound upon its drum the platform will be raised.

In the form of platform shown in Figs. 1, 25 2 and 3 the extension arms are raised into vertical position as the platform is lowered from the upper end of the guides 5, the extension arms inclining against said guides. When the platform is raised to or above the 30 upper end of the guides 5 or into the position shown in Fig. 3 the arms 27 will have fallen outwardly over the upper ends of the guides 5 when they will rest upon the frame 1. This platform is loaded with lumber or the like to be raised to the floor at 35 the upper end of the guides 5. When this point is reached the extension arms will fall outwardly into such position that the load can gravitate from the platform over said 40 arms to the floor of the building, or to the false or temporary platform 4 and then to the floor of the building, the free end of the platform being raised relatively to the inner end as shown. Rubbish is removed 45 from the several floors of the building with the platform and frame shown in Fig. 4, the free end of the platform being tilted downwardly relative to its inner end. The frame is filled with rubbish and the hoist 50 lowered to a point just above the receiving cart or wagon, the sliding door 31 is then raised and the rubbish permitted to gravitate into the said cart. The platform shown

in Fig. 5 is raised to a level with the temporary building platform 4 when the wheelbarrows can be readily wheeled upon said platform and loaded or unloaded.

What is claimed is:—

1. In a hoist, channeled guides, means for securing said guides to a support, a sliding 60 frame operatively arranged in said channeled guides, a platform adjustably carried by said sliding frame, and actuating means for said sliding frame.

2. In a hoist, a travelling platform, supports for said platform, an adjustable frame comprising L-shaped angle pieces having their meeting ends overlapped, and braces connecting said supports and adjustable frame.

3. In a hoist, channeled guides, supports therefor, a sliding frame operatively arranged in said channeled guides, a platform adjustably carried by said sliding frame, and extension arms pivotally carried by said 70 platform and adapted to rest against said channeled guides when said platform is substantially below the upper ends of said guides, and to extend outwardly from said platform over the upper ends of said channeled guides when said platform is flush with or above the upper ends of said channeled guides.

4. In a hoist, channeled guides, supports therefor, a sliding frame operatively arranged in said channeled guides, a platform adjustably carried by said sliding frame, and extension arms pivotally carried by said 85 platform and adapted to rest against said channeled guides in vertical position when 90 said platform is substantially below the upper ends of said guides, and to extend outwardly from said platform over the upper ends of said channeled guides and to rest upon said supports when said platform is 95 flush with or above the upper ends of said channeled guides.

In testimony that I claim the foregoing as my own I have hereto affixed my signature in the presence of two subscribing witnesses.

CHARLES B. JOHNSON.
